UNITED STATES PATENT OFFICE

HOMER J. VETTER, OF NEWTON, KANSAS

DESIGN FOR A COMBINATION COMB AND BRUSH

Application filed June 13, 1931. Serial No. 40,202. Term of patent 7 years.

To all whom it may concern:

Be it known that I, HOMER J. VETTER, a citizen of the United States, residing at Newton, Harvey County, State of Kansas, have invented a new, original, and ornamental Design for Combination Comb and Brush, of which the following is a specification, reference being had to the accompanying drawings, forming a part thereof.

In the drawings:

combination comb and brush, showing my new design;

I claim:

The ornamental design for a combination comb and brush as shown.

HOMER J. VETTER.
